M. S. BLACK

PACKING HEAD FOR WELL CASINGS

Filed Jan. 4, 1923

Inventor:

MILLARD SUMTER BLACK

By Hazard & Miller

Attorneys

UNITED STATES PATENT OFFICE.

MILLARD SUMTER BLACK, OF BREA, CALIFORNIA.

PACKING HEAD FOR WELL CASINGS.

Application filed January 4, 1923. Serial No. 610,668.

To all whom it may concern:

Be it known that I, MILLARD SUMTER BLACK, a citizen of the United States, residing at Brea, in the county of Orange and State of California, have invented new and useful Improvements in Packing Heads for Well Casings, of which the following is a specification.

My invention relates to packing heads for well casings, and a purpose of my invention is the provision of a packing head which operates to provide an effective seal between a well casing and tubing for preventing the passage of liquid and slush upwardly between the two, my invention being constructed to permit of its application to tubings of different diameters and of allowing the ready application and removal to and from the casing.

Although I will describe only one form of packing head for well casings embodying my invention and point out the novel features thereof in claims, it is to be understood that various changes and modifications may be made herein without departing from the spirit and scope of such claims.

In the accompanying drawings,

Figure 1 is a view showing in vertical section a well casing and tubing having applied thereto one form of packing head embodying my invention.

Fig. 2 is a top plan view of Fig. 1.

Fig. 3 is a transverse sectional view taken on the line 3—3 of Fig. 1.

Similar reference characters refer to similar parts in each of the several views.

Referring specifically to the drawings and particularly to Fig. 1, I have here shown a well casing designated at K which is shown in position within a well, such casing being provided at its upper end with an extension E having openings in which pipes P are mounted and through which water and slush from the well is adapted to be delivered to a point exteriorly of the well. Above the pipe P the extension E is enlarged diametrically to provide a shoulder 15 grooved to receive a packing ring 16 and upon which is adapted to seat a false ring R. The false ring R is a bushing and the bushings are made in different sizes to fit various well tubing and various well casings. The false ring constitutes a part of the packing head embodying my invention, and such packing head also includes a positioning ring 17 arranged interiorly of the false ring R and engaging a

shoulder 18 formed adjacent the lower end of the latter. Above the positioning ring 17 are arranged a plurality of packing rings 19 adapted to be engaged by a gland 20 slidably fitted within the bore of the false ring and formed with an annular flange 21 engaged by a sleeve S threadedly mounted upon the extension E. The sleeve S is formed with a thickened portion 22 to provide a shoulder 23 which engages the flange 21, the inner surface of the sleeve being of conical form to accommodate cone-shaped slips 24.

As shown in Fig. 1, the well tubing T extends through the gland 20 of the packing head, the packing rings 19, positioning ring 17, and then downwardly into the well casing K. By the adjustment of the sleeve S, it will be clear that the gland 20 can be forced downwardly to cause the packing rings 19 to firmly embrace the tubing T and to thereby co-operate with the false ring R in preventing the passage of liquid or slush upwardly between the well casing and tubing.

It will be particularly noted that the tubing T shown in Fig. 1 is of relatively small diameter as this constitutes the lower portion of the tubing or the first portion that is introduced into the well casing. When adding sections of the same diameter it will be understood that it is necessary to remove the packing head as well as the slips 24.

From the foregoing description taken in conjunction with the accompanying drawings, it will be manifest that I have provided a packing head for well casings which effectively seals the joint between the casing and tubing and irrespective of the diameter of the tubing, and that the application and removal of the packing head to or from the well casing can be readily accomplished to facilitate the insertion or withdrawal of the tubing sections.

What I claim is:

1. A packing head for well casings comprising a casing extension having an annular shoulder formed interiorly thereof, a false ring resting upon said shoulder and engaging the interior of said extension substantially its complete length, a centering ring within the false ring, packing rings superimposed upon the centering ring, a gland movable upon the false ring, and a sleeve adjustable on the extension and engaging said gland.

- 2
2. A packing head for well casings comprising a casing extension having an annular shoulder formed interiorly thereof, and having a groove, a packing ring in the groove, a false ring sustained on the packing ring, a centering ring within the false ring, packing rings superimposed on the centering ring, a gland movable within the false ring, and a sleeve adjustable on the extension and engaging the gland for the purpose described. 30
3. A packing head for well casings comprising a casing extension having an annular shoulder formed interiorly thereof, a false ring sustained on the shoulder, a centering ring within the false ring, packing rings superimposed on the centering ring, a gland movable within the false ring, and a sleeve adjustable on the extension and engaging the gland, said sleeve being formed with a conical bore, and slips within said bore. 35
4. A packing head for well casings comprising a casing extension having a shoulder formed interiorly thereof and grooved, a packing ring in the groove, a false ring supported within the extension on the packing ring and having an inwardly extending shoulder at its lower end, a centering ring resting on the shoulder, packing rings with in the false ring upon the centering ring, a gland slideable in the false ring against the packing rings and having an outwardly extending flange at its upper end, and a sleeve adjustable on the extension and engaging the flange for forcing the gland into engagement with the packing rings. 40
5. A packing head for well casings comprising a casing extension, an annular shoulder formed interiorly thereof, a false ring disposed within the said extension with its lower edge engaging said shoulder, a centering ring within said false ring, packing rings superimposed upon said centering rings, a gland movable within the false ring, and a sleeve adjustable upon said extension and engaging said gland. 45

In testimony whereof I have signed my name to this specification.

MILLARD SUMTER BLACK.
